UNITED STATES PATENT OFFICE.

WILLIAM H. SHEPPARD, OF WORCESTER, MASSACHUSETTS, ASSIGNOR TO SHEPPARD ENVELOPE COMPANY, OF WORCESTER, MASSACHUSETTS, A CORPORATION OF MASSACHUSETTS.

ENVELOPE MACHINE.

Application filed November 29, 1922. Serial No. 604,059.

To all whom it may concern:

Be it known that I, WILLIAM H. SHEPPARD, of Worcester, in the county of Worcester and State of Massachusetts, a citizen of the United States, have invented a new and useful Improvement in Envelope Machines, of which the following is a specification.

My invention relates particularly to that portion of an envelope machine which is used for the purpose of applying to the open-faced envelope a patch of transparent material whereby the opening will be closed. Various means have been devised for accomplishing this result, but so far as I know such means have required either that the envelope blank should be stopped in its horizontal movement between the gumming mechanism and the folding mechanism during which delay the patch, so called, of transparent material shall be applied, or else has been applied at some point during the folding operation by means of, for example, the ordinary folder plunger by which the blank is carried down through the creasing frame onto the bottom of the folding box. In my machine hereinafter described the envelope blank moves in the usual way upon a carriage horizontally from the gummer to the folding box and during its transit and without stopping receives the patch which is applied by a rotary element to cover the opening in the blank.

An important advantage in a machine so constructed lies in the fact that there is no loss of time due to the stoppage of the blank during the attaching process and there is also no loss of power due to the change of direction of motion in the reciprocation of the plunger. Hence in the operation of my mechanism there is no jar such as always exists in a machine where a reciprocating motion is utilized.

In the drawings there is shown only so much of the envelope machine frame as is necessary to the proper disclosure of my invention. The mechanism shown is that relating solely to my invention, and it is shown in its preferred form mounted upon the envelope machine frame.

Figure 1 is a side view of mechanism embodying my invention.

Fig. 2 is plan thereof, the carriage being omitted.

Fig. 3 is a partial front elevation.

Fig. 4 is a partial rear elevation, and

Figs. 5 and 6 show, respectively, the machine in the act of securing a patch from the patch hopper and after dropping that patch on the patch feed.

60

In the drawings I have shown so much of an envelope machine as will indicate the means for supporting my mechanism, and as in the preferred construction of my machine I use suction for the purpose of lifting the top patch from the patches in the hopper as has been done in other machines, I have omitted from the drawings the suction pump and other means including the suction cut-off and means for operating it whereby suction may be applied and released at the proper times to lift and drop the patch, as such parts and the means for operating them are old in this art.

Various parts of the frame of the machine are lettered A, A¹, A², etc., as below referred to. Such parts being well known or easily recognized will not be further described except as may be necessary to describe the preferred construction and operation of my mechanism.

B is the carriage which as ordinarily constructed comprises two rests which are connected to run in guides on the part of the frame marked A¹, b being a hook applied to each member of the carriage by means of which the envelope blank is pulled from a position under the picker and gummer mechanism to some convenient point, for example, a point just beneath the patch-at-taching mechanism, as shown in Fig. 1. It will be understood that the carriage is constantly reciprocated by suitable and well known means and that the rests are spaced apart so that means may be provided between them whereby the blank may be fed to the folding box by feed rolls as shown or other means, without interference.

The mechanism shown comprises therefore mechanism for feeding the blanks continuously and without stoppage from the gummer to the folding box, means for picking up the patch and presenting it to the patch-feeding mechanism itself and the means for applying the patch to the blank while the blank is in motion. 1 is the power shaft which carries a sprocket wheel 2 connected by a sprocket chain 3 with sprocket 4 on the shaft 5, this shaft being supported on uprights A⁴. On the shaft 5 is mounted 100

105

110

a series of feed rolls 6 of such diameter that they will support and feed the envelope blank C and the patch c attached thereto. The shaft 5 also carries a gear 7 in 5 mesh with a gear 8 on shaft 9, this shaft being supported in the arms a^4 pivoted in bearings a^5 on the uprights A^4 . This shaft 9 carries presser rolls 10 segmental in character and serving during a portion of their 10 circumference to engage the patch, press it against the blank and at the same time co-operate with the feed rolls 6 in feeding the blank. Preferably these presser rolls are cut away as indicated at 11 so that during a 15 portion of their circumference they do not engage the feed rolls or blank. It is desirable that the shaft 9 be supported in a swingable arm so that the presser rolls may adjust themselves to the thickness of the 20 paper of which the blank is made and also to the additional thickness added thereto at the points where the patch is applied to the blank. It will be noted that these presser rolls serve also as a part of the patch-feeding 25 mechanism. A spring 101 attached at one end to the lug 102 on A^4 and at the other end to the end of a^4 pulls a^4 down to keep the rolls 10 in contact with the paper. 30 12 is the patch hopper which is mounted in fixed position on an arm or bracket 13. Preferably the connection between the hopper 12 and bracket 13 is such that in the first adjustment of the machine the hopper may be set at the proper angle to the patch 35 picker. The hopper comprises a platform from which project rods 14 and a stripper 15, this stripper being preferably a small metal plate which rides on two of the rods 14 and serves to prevent by its weight more 40 than one patch being lifted at a time.

The patch picker comprises a hollow box 16 of such size that when in contact with the top blank in the hopper as shown in Fig. 5 it will engage only a portion of the 45 surface of the top blank. It is perforated on its under surface in a manner well known and the chamber within it is connected by a tube 17 with a suction pump and suction control mechanism, which may be of any 50 well known kind. It is pivoted at 18 to a yoke 19 attached to an arm 20 forming the lower extremity of a plate 21. This plate 21 carries a bearing 22 and at its upper end is provided with an angle piece 23. A 55 spring 24 is connected at its lower end with the rear end of the picker 16 and at its upper end with an adjusting screw 25 which passes through the angle piece 23, the adjustment of the tension of the spring being 60 regulated by a thumb nut 26. The bearing 22 is mounted on a shaft 27 which carries a T-shaped lever 28 the lower arm of which has a cam roll 29 mounted on it. Its long arm is pivotally connected to a link 30 carrying a hub mounted on stud 301 which also

carries the hub of a second link 31 connected by a knuckle joint with a yoke 32 on the upper end of a rod 33. The stud 301 is mounted to turn in a bearing in bracket a^2 on upright A^2 . The lower end of rod 33 is 70 connected at 34 with an eccentric strap 35. 36 is an eccentric mounted on the shaft 37 which carries also a gear 38 in mesh with a gear 39 on the shaft 1.

It will be noted from this construction 75 that the rotation of the shaft 1 will thus cause the rise and fall of the rod 33 and it in turn will cause the link 31 and lever 28 to move toward the right from the position shown in Figs. 1 and 5 to the position 80 shown in Fig. 6, thus causing the lifting of the patch picker and its movement into patch-releasing position, and it will also be understood that by means of mechanism now well known in the art suction will be applied 85 to the picker so that when in picking position the top patch in the hopper will be attracted and for the moment attached to the under surface of the picker which during its feeding movement will pull the patch 90 out from under the stripper 15 and carry it over to a predetermined point and then release the patch so that it will fall onto the patch feed. For this purpose the cam roll 29 is caused to run over a cam surface 40 95 mounted on a portion of the frame A^3 . This will cause the picker 16 to rise into position properly to discharge the patch onto the patch-feeding mechanism.

The patch-feeding mechanism comprises 100 a series of belts preferably of canvas or some material from off which the patch will not readily slip. Such belts are shown at 41. A number of these belts are used and all of them pass over pulleys 42, 43. The 105 pulleys 42 are mounted on a shaft 44 supported in bearings on the uprights A^5 and carrying at its outer end a sprocket 45. This sprocket is connected by a sprocket chain 46 with a sprocket 47 on the further 110 end of the shaft 9. The pulleys 43 are mounted on a shaft 48 which is carried by links A^7 hanging from shaft 49 which passes through frames 50. This shaft also carries check levers 491 each having a toe 51 adapted to engage the patch at the proper time and hold it until the attaching mechanism is ready to receive it. For this purpose these levers, of which there may be any convenient number (two are shown), are held 115 in lowered position as shown in Fig. 6 by means of a spring 52 one end of which is attached to the frames 50 and the other end of which engages the pin 53 on the lever 491. To lift this lever 491 at the proper time I provide a suitably shaped cam 54 mounted on the shaft 9 to turn therewith. It has projections which engage the lever 491 at the proper times, the lever having 120 preferably an adjustable screw or bearing 125 55 which is held in the lever 491 by a set screw 56. The lever 491 is pivoted to the frame 50 at 57 and has a toe 51 which is adapted to engage the patch 130

surface 55 so that the throw of the lever may be easily controlled.

In order to serve as a guide to the patch I provide belts 56 passing round pulleys 57, 58. The pulleys 58 are mounted on a shaft 59 mounted in the frames 50 carrying a gear 60 which is in mesh with the gear 8. The pulley 57 is mounted on a stud 61 carried by the frames 50 through the front end 10 of which the shaft 59 passes. They serve to support the various parts in proper relation to each other. The pulleys 57, 58 are so arranged that the belt moves within a short distance of the feed belt 41 and thus, 15 while not engaging the patch, guides it as it leaves the patch picker to the feed belt and prevents its lateral edges from curling up so that the patch will be fed properly by the feed belt.

20 The patch being carried down by the belt 41 engages rolls 63 which is preferably coated with rubber or other like material. These rolls 63 are mounted on a shaft 64 carried by an arm 65 projecting downward 25 from the frame 50. The shaft 64 has on it a gear 66 which is in mesh with the gear 8 so that it is given a positive motion to press the patch against the pressing surface of the presser wheel 10 and ensure contact between 30 the two. A guiding plate 67 is hung from the arms 65 and guides the patch so that it is properly presented to the envelope blank.

From the above it is believed that the operation of my invention will be understood. 35 The various parts of my machine are timed so that suction being applied and the picker approaching or resting upon the top patch in the hopper will engage it, lift it out from under the separator and carry it up and over to such a position that upon the releasing of the suction the patch will drop onto the feeding belt as shown in Fig. 6 where the patch is lettered *c*¹. The position and movement of the belt 56 is such as to 40 guide the patch onto the feeding belt by which it will be carried down. At the same time the toe 51 of the lever 491 will be lifted by the cam so as to engage and hold the lower edge of the patch until the patch is wanted. In the meantime the envelope 45 blank, which has had its window previously cut therein, has been moved into a position under the pressing mechanism when the lever 491 being released by its cam will be pulled back by gravity, and its spring thus 50 releasing the patch and allowing it to pass down into engagement with the rubber roll 63 and the pressing surface of the presser roll 10. It is thus fed along into proper 55 position between the feed rolls and the presser rolls and it is thereby attached along its edges to the blank which has been previously suitably gummed by the gumming mechanism.

60 It will be understood that during this op-

eration there is no delay or dwell to the envelope blank. It may be fed continuously from the gumming mechanism to the folding mechanism, the patch-applying mechanism assisting in its feed, the patch-applying mechanism thus being available at any time in case it is desired to use the machine to make ordinary envelopes without the open face.

65 It will be noted that only six feed or presser rolls are shown; in other words, that pressure is only applied at six different points. The number is immaterial for in the subsequent handling of the blank, either in the folding box or in the drier, close contact is made between the patch, the gummer and the blank.

70 It is also apparent that while my mechanism is primarily designed for applying patches to envelope blanks, it may equally well be used for applying address labels to newspaper wrappers or the like. And it is also apparent that while I have shown my invention embodied in the best form now known to me, I do not mean to limit myself 75 to the exact construction shown as its details may be varied without departing from my invention.

80 What I claim as my invention is:—

85 1. In a machine of the kind described, a patch hopper and means for applying a patch from said hopper to an envelope blank comprising a horizontally-reciprocating blank feed adapted to carry the gummed blank from a pile of blanks to a folding mechanism, and means for applying said patch to said blank while said blank feed 90 is in motion.

95 2. In a machine of the kind described, a hopper, means for selecting a patch from said hopper, a continuously reciprocating blank feed, a patch feed, means for carrying the patch from said hopper to said patch feed, whereby it will be fed to a moving blank carried by said blank feed.

100 105 3. In a machine of the kind described a hopper, means for selecting a patch from said hopper, a continuously moving blank feed, a patch feed, suction means for carrying the patch from said hopper to said patch feed whereby it will be fed to a moving blank carried by said blank feed.

110 115 4. In a machine of the kind described, a patch-handling mechanism comprising a patch picker, means for moving it from a patch-picking to a patch-delivery position, a patch feed comprising a moving belt located to receive a patch from said patch picker, and deliver it to a presser mechanism, and a presser mechanism comprising a presser roll, in combination with a blank feed, rolls located to register with said presser rolls whereby said patch will be pressed onto a blank carried by said blank feed.

120 125 5. In a machine of the kind described, a

130

- patch-handling mechanism comprising a patch picker, means for moving it from a patch-picking to a patch-delivery position, a patch feed comprising a moving belt located to receive a patch from said patch picker, and deliver it to a presser mechanism, and a presser mechanism comprising a presser roll, and means for holding said patch against said presser roll, in combination with a blank feed, rolls located to register with said presser rolls whereby said patch will be pressed onto a blank carried by said blank feed.
6. In a machine of the kind described, a patch-handling mechanism comprising a patch picker, means for moving it from a patch-picking to a patch-delivery position, a patch feed comprising a moving belt located to receive a patch from said patch picker, and deliver it to a presser mechanism, and a presser mechanism comprising a presser roll, and yielding means for supporting said presser roll, in combination

with a blank feed, rolls located to register with said presser roll whereby said patch will be pressed onto a blank carried by said blank feed.

7. In a machine of the kind described, a patch-handling mechanism comprising a patch picker, means for moving it from a patch-picking to a patch-delivery position, a patch feed comprising a moving belt located to receive a patch from said patch picker, and deliver it to a presser mechanism, and a holding lever and means for moving it intermittently into the path of a patch on said feeding mechanism and then releasing said patch whereby the delivery of said patch to said presser mechanism may be positively timed, and a presser mechanism comprising a presser roll, in combination with a blank feed, rolls located to register with said presser roll whereby said patch will be pressed onto a blank carried by said blank feed.

WILLIAM H. SHEPPARD.
